UNITED STATES PATENT OFFICE.

EDWARD R. HALL, OF QUINCY, MASSACHUSETTS, ASSIGNOR TO HOOD RUBBER COMPANY, OF WATERTOWN, MASSACHUSETTS, A CORPORATION OF MASSACHUSETTS.

DESIGN FOR A TIRE.

Application filed February 29, 1924. Serial No. 8,789. Term of patent 14 years.

To all whom it may concern:

Be it known that I, EDWARD R. HALL, a citizen of the United States, residing at Quincy, in the county of Norfolk, Massachusetts, have invented a new, original, and ornamental Design for Tires, of which the following is a specification, reference being had to the accompanying drawing, forming a part hereof.

Figure 1 is a developed plan view.

Fig. 2 is a transverse section taken on line 2—2 on Fig. 1.

I claim:

The ornamental design for a tire, as shown.

EDWARD R. HALL.
